UNITED STATES PATENT OFFICE.

WILLIAM L. MURPHY, OF SAN FRANCISCO, CALIFORNIA, ASSIGNOR TO MURPHY WALL BED COMPANY, OF SAN FRANCISCO, CALIFORNIA, A CORPORATION OF CALIFORNIA.

FOLDING BED.

1,218,202.

Specification of Letters Patent. Patented Mar. 6, 1917.

Application filed August 17, 1914. Serial No. 857,127.

To all whom it may concern:

Be it known that I, WILLIAM L. MURPHY, a citizen of the United States, and a resident of the city and county of San Francisco, State of California, have invented certain new and useful Improvements in Folding Beds, of which the following is a specification.

The invention relates to folding beds and particularly to such beds which are adapted to fold upward on a horizontal axis and be folded into or moved into a closet or recess.

An object of the invention is to provide a folding bed which when folded is of minimum depth, and this is accomplished without sacrificing any of the room or space necessary for the reception of the mattress, bed clothes and pillows.

Another object of the invention is to provide a folding bed, which when folded is of minimum height, and this is accomplished without folding the bed frame on itself. The length of the standard bed frame is approximately six feet four inches and the height of a standard door is approximately six feet eight inches, and it is one of the objects of this invention to provide a standard bed which may be folded into, or when folded may be moved into, a closet or recess which is adapted to be closed by a standard door. In other words, one of the objects of the invention is to provide a bed which when folded occupies a minimum of space, without sacrificing mattress and pillow room, and without shortening the length of the bed. The construction of the bed is such, that when folded the supporting and operating mechanism lies between the front and rear of the folded structure, so that no extra depth is necessary to accommodate these elements.

Another object of the invention is to provide means for controlling the movement of the pivoted head frame as the bed is being folded and unfolded, and a further object is to provide improved means for counterbalancing the weight of the bed.

The invention possesses other advantageous features, some of which, with the foregoing, will be set forth at length in the following description, where I shall outline in full that form of the invention which I have selected for illustration in the drawings accompanying and forming part of

the present specification. In the drawings I have shown only one specific form of my generic invention, but it is to be understood that I do not limit myself to such form, because my invention may be embodied in a multiplicity of forms, each being a species of my said invention. It is also to be understood that by the claims succeeding the description of my invention, I desire to cover the invention in whatever form it may be embodied.

In the drawings:

Figure 1 is a side view of the folding bed of my invention, the bed being shown in the horizontal or unfolded position, and part thereof being broken away to reduce the size of the figure.

Fig. 2 is a side view of the folding bed of my invention, the bed being shown in the vertical or folded position and being disposed in a recess, part of the structure being broken away to reduce the size of the figure.

Fig. 3 is a section of a portion of the bed of my invention taken on the line A—A Fig. 1.

In homes, hotels, apartment houses and the like, space is a very valuable consideration, and the same reasons which demand a folding bed, demand that the bed when folded occupy as small a space as possible. This demand I have fulfilled by the present bed, without lessening the space necessary in the bed for the reception of the mattress, bed clothing and pillows, so that these articles may remain in place on the bed when folded, and without lessening the length of the bed.

The bed of my invention comprises a bed frame formed in part of the side rails 2, the foot rail 3 and the fixed head 4, which is rigidly attached to the side rails. The fixed head 4 is of such height that it extends above or to the level of the top of the pillows when the mattress, bed clothing and pillows are in place on the bed. Pivoted to the fixed head is the head frame 5, which is controlled in its movement so that when the bed frame is in the horizontal or vertical position the head frame is vertically disposed, and the controlling means is such that the head frame is held in a substantially vertical position during the folding and the unfolding of the bed.

The bed frame is pivotally mounted on links 6 arranged on opposite sides of the

bed frame, and the links are pivoted at their lower ends to brackets or lugs 7, which are secured to the floor or other structure. The pivot pin 8 between the link 6 and the bed frame lies in the plane of the side rails 2 and is spaced from the near end of the rail a distance slightly less than the length of the link.

Arranged at opposite sides of the bed in the angle between the side rails and the head frame are brackets 9 on which occur pins 12 which are disposed above the plane of the side rails when the bed frame is in the horizontal position. Each pin engages a stationary guide 13, which is preferably formed integral with the lug 7. The guide is provided with a shoulder 14 adjacent its upper end on which the pin 12 seats when the bed frame is horizontal, thereby locking the frame in such position. The guide is inclined backwardly at such an angle that when the bed frame reaches the vertical position the upper end of the fixed head, or that end to which the head frame is pivoted, lies almost in contact with the rear wall of the recess, thereby eliminating any waste room. When the bed is in the vertical position, the links 6 are substantially vertical and do not extend beyond the bed rails, thereby causing no waste of room at the front of the folded bed.

The movement of the head frame 5 and its position when stationary is controlled by the link 15, pivoted at one end to the head frame, and at the other end to an arm or extension 16 on the link 6. The position of the connection between the link 15 and the extension 16 is so placed with relation to the positions of the other pivots, that when the bed frame is horizontal the head frame is vertical and when the bed frame is vertical, the head frame is vertical and the head frame remains substantially vertical during the folding or unfolding movement of the bed frame.

In the manufacture of beds the various pivots and links are cast, so that there is more or less play at the pivotal connections, and since when the bed frame is in a vertical position, three pivotal points are almost alined, there may be considerable independent movement of the head frame about its pivot. To prevent this independent movement I fix a pin or abutment 17 on the link 15 which is arranged to contact with the head frame when the bed frame is in the vertical position.

The bed frame is counterbalanced by means of a spring or springs 18 arranged transversely below the bed frame. When the double spring construction is employed, one end of the spring may be attached to an eye bolt which is adjustably secured to a stationary element preferably formed integral with the lug and guide at one side of

the bed, and the other end of the spring is attached to a cord or cable 19 which passes under a roller 21 arranged at the opposite side of the bed, and which is attached to the pin 12. As the bed frame is lowered or unfolded, the spring is extended, and as the bed frame is folded, the spring contracts. When a single spring is employed, the cables are attached to the opposite ends of the spring, and in one of said cables or in each of them, a turnbuckle or other means may be inserted for the purpose of permitting the length of same to be adjusted. By arranging the counterbalancing springs horizontally and transversely below the bed frame, no extra space is necessary for the springs, and the bed is foldable into a small space.

I claim:

1. In a folding bed, a bed frame adapted to swing from a horizontal to a vertical position, a head frame pivotally mounted on said bed frame, supporting links for said bed frame, pins on said bed frame journaled in said links, and means connecting one of said links with the head frame for maintaining the head frame in a substantially vertical position when the bed frame is in its vertical or horizontal position.

2. In a folding bed, a bed frame, a fixed head on said frame, a head frame pivoted to said fixed head, supporting links attached to said bed frame, and means connecting one of said links with the head frame for maintaining the head frame in a substantially vertical position as the bed frame is folded and unfolded.

3. In a folding bed, a bed frame, a fixed head on said frame, a head frame pivoted to said fixed head, supporting links attached to said bed frame, and a link connecting one of said supporting links with the head frame, said link maintaining the head frame in substantially a vertical position as the bed frame is folded and unfolded.

4. In a folding bed, a bed frame, a fixed head on said frame, a head frame pivoted to said fixed head, supporting links attached to said bed frame, an extension on one of said links projecting above the plane of the bed frame when it is in a horizontal position, and a link connecting said extension and the head frame.

5. In a folding bed, a bed frame, a fixed head on said frame, a head frame pivoted to said fixed head, supporting links attached to said bed frame, a link connecting one of said supporting links with the head frame, and an abutment on said connecting link adapted to contact with the head frame when the bed frame is in a vertical position.

6. In a folding bed, a bed frame, a fixed head on said frame, a head frame pivoted to said fixed head, supporting links pivoted to said bed frame in the plane of the frame,

- guides arranged at opposite sides of the bed frame, pins on said bed frame disposed above the plane of the frame when it is in a horizontal position engaging said guides, 5 and a link connecting said head frame with one of the supporting links, whereby the head frame is maintained in a substantially vertical position when the bed frame is in its vertical or horizontal position.
- 10 7. In a folding bed, the combination of a bed frame adapted to be moved from a horizontal to a vertical position, a mounting to which said bed frame is pivoted, a head frame pivoted to the bed frame and a link connecting said head frame to the mounting 15 at a point forward of said head frame and spaced from said bed frame pivot for maintaining said head frame in a substantially vertical position when the bed frame is in its horizontal or vertical position. 20

In testimony whereof, I have hereunto set my hand at San Francisco, California, this 11th day of August, 1914.

WILLIAM L. MURPHY.
